UNITED STATES PATENT OFFICE.

HARRY C. HOLMES, OF MACOMB, ILLINOIS.

MORTAR-HOE.

1,127,440.

Specification of Letters Patent.

Patented Feb. 9, 1915.

Application filed April 1, 1914. Serial No. 828,935.

To all whom it may concern:

Be it known that I, HARRY C. HOLMES, a citizen of the United States, residing at Macomb, in the county of McDonough, State 5 of Illinois, have invented certain new and useful Improvements in Mortar-Hoes; and I do hereby declare the following to be a full, clear, and exact description of the invention, such as will enable others skilled in the art to 10 which it appertains to make and use the same.

This invention relates to a mortar hoe.

An object of the invention is to provide for the thorough mixing of mortar or like 15 material.

A further object of the invention is to provide a device wherein the mortar will be more thoroughly mixed and mixed in a shorter time than has been possible with any 20 previously existing hoes.

Referring to the drawing: Figure 1 is a side elevation of my device. Fig. 2 is a section on line 2—2 of Fig. 1.

Referring to the drawing by reference 25 characters wherein like characters represent like parts throughout the several views, my invention comprises a body portion 1 having a centrally located transverse bar 2. Formed on either side of this bar 2 are angularly disposed vanes arranged in pairs, 30 the inner pair 3 of which is disposed at an angle to the outer pair 4. These vanes are struck from the material of the hoe and extend in angular relationship to the plane of 35 the body portion 1 and to each side of the said plane. The inner pairs 3 of the vanes are arranged at acute angles to the middle bar 2 and extend outwardly from the said bar at the rear side of the body member 1 and 40 away from the said bar at the front side of the body member, while the outer pairs are arranged in directly opposite relation to the central bar 2, that is they are directed away from the said bar on the rear side of the hoe, 45 but toward the bar on the front side. It is of course understood that when the vanes are struck from the body member 1 and turned into the positions just described slots are formed between the said members.

When the hoe is pushed forwardly by the 50 handle 5 in mixing mortar, the mortar will be pushed through the apertures 3' and directed inwardly toward the central bar 2 by the vanes 3, thus throwing the mortar which enters on each side of the bar together 55 and thoroughly intermixing the same. It is of course understood that as the hoe is pushed in this direction, the mortar will be forced through the slots 4' and although it will not be mixed as is that which is forced 60 through the slots 3' it will facilitate the mixing of the mortar to a great extent. When the hoe is drawn rearwardly the mortar is forced through the slots 3' and 4' from the rear of the hoe on each side of the middle bar 65 2 and the mortar which is forced through the slots 4' is directed inwardly, while the mortar which is forced through the slots 3' is directed outwardly by the vanes, and that which is forced through the slot 5' passes 70 through the hoe at a right angle to the plane thereof. It may thus be seen that when a hoe is drawn rearwardly the mortar will be thrown together in such a way that it will be thoroughly mixed on each side of the 75 bar 2.

It is to be understood that although I have described the particular construction of the device illustrated, it is merely for convenience that I have selected the particular form, for 80 I may make the device with any number of vanes on either side of the central bar, or may arrange them at any angle with relation to the body of the device.

From the foregoing description it may 85 be seen that I have provided a simple and efficient device, wherein, when mixing mortar, portions of the same will be thrown together so that they will not only be mixed in a shorter time than is possible with the 90 old devices, but will also be more thoroughly mixed than has been previously possible.

I do not wish to be limited by the specific embodiment shown, but only so far as is necessary by the claim.

What is claimed is:—

In a device of the class described, a body

member having a middle bar formed thereon, slots arranged on each side of said bar, a pair of vanes adjacent said bar on each side thereof, and arranged at angles to the said middle bar and extending on each side of the plane of the body portion, and pairs of vanes on each side of the middle bar beyond said first mentioned vanes and in angular

relationship to the body portion reverse to that of the first mentioned pair of vanes. 10

In testimony whereof, I affix my signature, in the presence of two witnesses.

HARRY C. HOLMES.

Witnesses:

T. ERNEST SWITZER,
THEODORE B. SWITZER.
